United States Patent Office

Des. 215,955
Patented Nov. 11, 1969

215,955

CLOCK

Giacinto C. D'Ercoli, Forest Park, Ill., assignor to General
Time Corporation, Stamford, Conn., a corporation of
Delaware

Filed Nov. 13, 1968, Ser. No. 14,421

Term of patent 14 years

Int. Cl. D10—01

U.S. Cl. D42—7

FIG. 2

FIG.4

FIG.3

FIG. 1 is a front elevational view of a clock showing my new design;

FIG. 2 is a top plan view, the bottom being substantially a mirror image of the top;

FIG. 3 is a right side elevational view, the left side being substantially a mirror image of the right side; and

FIG. 4 is a rear elevational view.

I claim:

The ornamental design for a clock, substantially as shown and described.
